9 Claims. (Cl. 250—27)

The present invention relates to detector circuits, and more particularly to improved methods of and means for, grid detection.

Two methods of using electron discharge tubes for detecting signal modulated high frequency energy are well known in the art. The first of these, commonly called grid detection, employs a grid condenser and grid leak resistance, connected in the well known manner, and effects rectification or detection of the impressed signal modulated energy by virtue of the curvature of the grid current-grid voltage characteristic curve of the electron discharge tube. The second method, commonly called plate detection, utilizes the curvature of the plate current-grid voltage characteristic curve to effect rectification or detection, the circuit being substantially the same as would be used with the same electron discharge tube as an amplifier except that a greater negative grid bias is required.

Grid detection has been used almost exclusively in the past because of its greater sensitivity, especially for the relatively small inputs heretofore available. But with recent developments in radio frequency amplification, and the present advantages of reduced audio amplification in minimizing "hum" in alternating current operated radio receivers, efficient detection of much larger inputs is urgently needed. To meet this need, plate detection has been used, this method being more sensitive for large inputs than for small inputs, the reverse being true of the heretofore known forms of grid detection. However, plate detection at its best, is relatively insensitive compared with grid detection of small input.

It is, therefore, highly desirable to provide an improved method of operating an electron discharge tube for grid detection of large inputs, such that greater sensitivity and maximum audio frequency output may be obtained than with any heretofore known form of grid detection. The method of obtaining such improved operation will be most clearly set forth following a brief general description of the process of grid detection, which will show the cause of the insensitivity for large inputs, of the usual forms of grid detectors.

When an audio frequency modulated radio frequency voltage of sufficient magnitude is impressed on the grid of the usual form of grid detector, grid current flows, and because of the curvature of the grid current-grid voltage characteristic curve, rectification takes place, and this current has both radio frequency and audio frequency components. These components of grid

current, flowing through the external grid circuit impedance, produce voltages at the grid equal to the product of current and impedance. These voltages, as well as the voltage originally impressed on the grid all affect the plate current in accordance with the plate current-grid voltage characteristic of the tube, and if the resultant instantaneous plate current varies over a non-linear portion of that characteristic curve, further rectification, i. e., plate detection occurs.

If this plate detection occurs at the lower bend in the plate current-grid voltage characteristic curve, as is usually the case, the resulting audio frequency component of plate current is opposed in phase to the audio frequency component of plate current produced by amplification without detection in the plate circuit of the audio frequency component of grid voltage produced by the grid detection. This opposing and, hence undesirable, plate detection effect is negligible with small inputs such as have heretofore been used with grid detector circuits. But, if it is attempted to use the method of grid detection with increasingly larger inputs, it is found that this plate detection effect increases in magnitude and importance, resulting in a greater decrease in sensitivity or efficiency, until a point is reached beyond which an increase in input causes an actual reduction in audio frequency output.

Thus, the maximum audio frequency output obtainable from a grid detector is ordinarily limited by the peak value of the instantaneous alternating plate current, since this determines the magnitude of the opposing and undesired plate detection. With the usual grid detector circuit this peak value of the instantaneous alternating plate current is much larger than the peak value of the audio frequency component of plate current, since a large radio frequency component is produced by the radio frequency component of grid voltage. The maximum audio frequency output obtainable from a given electron discharge tube as a grid detector is therefore considerably less than would be obtainable from the same tube used as an audio frequency amplifier.

It follows then, that if the flow of radio frequency current in the plate circuit of the detector tube were suppressed, a considerably greater audio frequency output could be obtained with a given input. The factor limiting the maximum audio frequency output would then be the distortion of the audio frequency output analogous to that which would occur if the same tube were used as an audio frequency amplifier. Concisely stated, a grid detector combines the functions of

detection in the grid circuit, with audio frequency amplification, and although the useful effects of the impressed radio frequency voltage stop with the production of the audio frequency voltage at the grid, they continue, unless preventive means are provided, into the plate circuit, to the detriment of the function of audio frequency amplification.

Now I have discovered, in operating an electron discharge tube as a detector, and particularly as a grid leak detector of audio modulated high frequency energy, that the high frequency component in the detector anode circuit may be substantially reduced, or suppressed, by producing a high frequency voltage at one of the electrodes of such a magnitude and phase with respect to the high frequency voltage on the control electrode of the detector, as to partially, or completely, compensate for the latter, thereby obtaining a considerably greater audio output for a given signal input than has heretofore been secured with detectors.

It is, therefore, one of the main objects of my present invention to provide preventive means, for reducing or eliminating the effect of the radio frequency component of grid voltage on the plate current of an electron discharge tube used for grid detection.

A further important object of the invention is to reduce or suppress radio frequency components of plate current.

Another important object of my present invention is to provide a method of, and means for, operating an electron discharge tube as a detector of signal modulated radio frequency energy, and particularly as a grid leak detector, which consists in employing, in addition to the usual anode, cathode and control electrode, an auxiliary electrode, and producing on the latter a radio frequency voltage of such magnitude and phase, as to substantially balance out the effect of the control electrode radio frequency voltage on the anode current, thereby increasing the audio output of the detector.

Another object of the invention is to provide a method of, and means for, employing an electron discharge tube, the latter having at least an anode, cathode, and control electrode, as a detector of signal modulated radio frequency voltages of large magnitudes, which consists in employing the radio frequency component of the signal input to produce a radio frequency voltage of such magnitude and phase as to suppress or reduce the radio frequency component in the detector anode circuit.

Another object of the invention is to provide means for detecting signal modulated radio frequency energy, the means comprising an electron discharge tube having besides the usual anode, cathode, and control electrode, one or more auxiliary electrodes, at least one of the latter being utilized to suppress or reduce the flow of radio frequency current in the detector anode circuit, thereby increasing the flow of audio frequency current therein.

Still another object of the invention is to provide a method, and means for, operating a triode, tetrode or a pentode as a power detector of signal modulated radio frequency voltages of large magnitudes.

Still other objects of the invention are to improve generally the efficiency of the electron discharge tube, as the triode, tetrode or pentode, used as a detector, and to, additionally, provide a detector of the grid leak type which is not only

reliable and efficient in operation but possesses greater sensitivity and maximum audio frequency output, and is economically introduced in a receiving circuit.

The novel features which I believe to be characteristic of my invention are set forth in particularity in the appended claims, the invention itself, however, as to both its organization and method of operation will best be understood by reference to the following description taken in connection with the drawing in which I have indicated diagrammatically several circuit organizations whereby my invention may be carried into effect.

In the drawing,

Fig. 1 diagrammatically shows a receiving circuit embodying one form of the invention,

Figs. 2 to 5 inclusive show modified forms of the invention,

Fig. 6 shows the invention embodied in still another form,

Fig. 7 discloses another modification of the invention.

Referring to the accompanying drawing in which like characters of reference indicate the same elements in the different figures, there is shown in Fig. 1 a receiving circuit comprising means for collecting signal modulated radio frequency energy, such as a grounded antenna circuit, A, G, the latter being coupled, as at M, to a radio frequency amplifier consisting of one, or more stages of amplification, arranged in any well known manner. The output circuit of the amplifier is coupled, as at M', to the input circuit of an electron discharge tube 1.

The tube 1, and its associated circuits, are arranged to operate as a detector of the amplified radio frequency energy, the specific type of detection employed in the circuit shown in Fig. 1, being of the so-called grid leak type of detection. The latter detection is secured by connecting a capacity 3 in series with the control electrode 4 of the tube 1, and connecting a leak resistance 5 between the control electrode 4 and the cathode 6. This type of detection is well known to those skilled in the art, and need not be explained any further in great detail. The tube 1 is preferably of the screen grid type, the tube including a screen element 7, the anode of the tube receiving potential from a source B through a resistor 8, the latter being connected in series between the anode and the positive terminal of the source B.

The negative terminal of the source B is connected to the cathode at a point to which the resistor 5 is connected, the said point being also connected to the positive terminal of the source B through a fixed capacity 9. Positive potential is applied to the screen element 7 from the source B, or any other source of positive potential, through an element 10 possessing a high impedance to radio frequency current, and shown herein as a radio frequency choke. The low potential end for alternating current of the choke 10 is connected to the negative terminal of the source B through a by-pass capacity 11. The rectified output of the detector tube 1 is transmitted, by means of the resistance-capacity coupling, which includes the resistor 8 and a capacity 12, to the input terminals of an audio system, the latter being for example an audio amplifier comprising one or more stages of amplification, or any other system adapted to utilize the rectified output of the detector 1.

The radio frequency choke 10 is inserted in series with the screen element 7, to reduce, or

eliminate, the effect of the radio frequency component of the control electrode voltage, on the anode current, thus permitting a larger audio current in the anode circuit of the detector tube. 5 If the voltage on the control electrode 4 is considered as composed of a radio frequency and an audio frequency component, it will be seen that with respect to the audio component, the tube 1 behaves as an ordinary screen grid amplifier, in view of the fact that the impedance between the screen element 7 and the cathode is 10 low to audio frequencies.

However, the screen element circuit will have a high impedance to radio frequencies, this being due to the insertion of the choke 10 in the screen circuit, thus resulting in a variation of screen element potential at radio frequency, this variation being wholly, or partially, out of phase with the radio frequency voltage on the control electrode 4. Accordingly, there results a substantial decrease in the radio frequency component of anode current flowing through the anode circuit of the detector tube 1.

While the presence of high impedance to radio frequencies in the screen element circuit will cause reaction between the screen element circuit and the control electrode circuit, such reaction may be rendered innocuous by any of the methods ordinarily employed in radio frequency amplifiers, such methods being well known to those skilled in the art. As a matter of fact, this reaction between the control electrode and screen element circuits may be used to advantage to increase the sensitivity of the circuit, thereby providing, in fact, a regenerative detector.

While the tube 1 has been shown as a screen grid tube, it is to be clearly understood that this type of tube need not be necessarily used for the success of the present invention. When a screen grid tube is utilized, the current in the anode circuit, of any frequency, can be limited to a small value, by employing in the screen grid circuit, a circuit element having high impedance to the frequency desired to be limited. From another point of view, although not necessarily the only explanation possible, the explanation for this phenomenon may be based upon the fact that current tends to flow in the screen grid circuit in phase with the anode current, or 180° out of phase with the control electrode voltage.

When a high impedance is inserted in the screen grid circuit, this current produces a voltage out of phase with the control electrode voltage, and therefore, tending to balance out the effect of the control electrode voltage on the anode current. It is obvious that the same effect may be secured by impressing the required voltage upon the screen element from any other source.

It is to be clearly understood that the amplifier preceding the grid leak detector is adapted to impress voltages upon the control grid circuit of the detector of such magnitude that, without the inclusion of the present invention, plate detection attains proportions such that an increase in input to the detector causes an actual reduction in audio frequency output of the detector. In other words, the present invention provides a method of operating a grid leak detector with radio frequency signal inputs of ordinarily prohibitive magnitude with the same efficiency and sensitivity as with relatively small radio frequency signal inputs. This is accomplished generally, by preventing the condition conducive to plate rectification.

For example, while I have shown in Fig. 1 the required high impedance in the screen grid circuit obtained by means of a radio frequency choke, in Fig. 2 there is shown a method of obtaining the required high impedance in the screen grid circuit by disposing a tuned circuit in series with the screen element 6. This tuned circuit consists of a variable capacity 13 connected between the high potential terminal of the choke 10 and the negative terminal of the source B. The tuned circuit 13, 10 offers a high impedance to the flow of radio frequency current in the screen grid circuit, and, moreover the phase of the resultant voltage of the screen grid may be adjusted accurately by virtue of the adjustability of the variable capacity 13.

In Fig. 3, there is shown still another method for accomplishing the result secured in the forms shown in Figs. 1 and 2, by the use of inductive coupling between the anode circuit of the detector tube 1 and the screen element circuit. By coupling the screen element 6 to the anode, through a radio frequency transformer, or other coupling system, compensation for the radio frequency component of anode current can be secured. The coupling consists of the radio frequency coil 10 inserted in the screen element 6 and a second radio frequency coil 14 connected in series between the anode of the tube and the resistor 8. A by-pass capacity 15 is connected between the high potential terminal of the resistor 8 and the negative terminal of the source B.

In this form of compensation, as in the forms hereinbefore described, a radio frequency voltage is caused to appear on the screen element of the tube 1 of such a magnitude and phase as to partially, or completely, compensate for the effect of the radio frequency component of control electrode voltage on the radio frequency component of anode current. It will be observed that in Fig. 3, the radio frequency component existing in the anode circuit, is employed for producing the compensating, or neutralizing, voltage on the screen element, thereby offering another mode of securing the required compensating voltage.

Still another mode of suppressing the radio frequency component of current in the detector anode circuit, (which is applicable to either simple triode or screen grid detectors, see Figs. 7 and 4 respectively), is to employ a high impedance in the anode circuit of the detector, the high impedance being a radio frequency choke 10' connected in series with the anode, a fixed capacity 15 being connected between the negative terminal of the source B and the choke 10'. A by-pass fixed capacity 16 is, also, connected between one end of the resistor 8 and the negative terminal of the source B.

In this modification the radio frequency choke coil in the plate circuit of the detector tube prevents the flow of radio frequency currents to the plate of the tube. By preventing the flow of the radio frequency current component in the plate circuit of the detector tube the detector overloading which occurs with increased signal input is effectively prevented, and the relation between detector output energy and signal input energy becomes substantially linear for signals of increased intensity. As explained heretofore substantially linear operation in a grid leak detector for signals of intensity above the normal overloading point can be prevented only by minimizing, or eliminating, the condition conducive to anode rectification. The effect of the radio

frequency choke in the external plate circuit of the modification, illustrated in Fig. 7 for example, is to substantially prevent radio frequency currents from flowing to the plate and through the plate circuit.

At this point, it may be observed that the limitation in audio output due to radio frequency current in the anode circuit may be explained by noting that rectification occurs in both the anode and grid circuits of a detector tube, and that these two effects are in phase opposition relation. Hence, by preventing the condition conducive to anode rectification (bias detection) the maximum audio output is increased; and, incidentally, the sensitivity.

In Fig. 5, there is shown still another modification of the invention, the anode circuit of the detector tube 1 including in this form, a variable capacity 13' and an inductance 10', the capacity being connected between the anode and the negative terminal of the source B. A fixed by-pass capacity 17 is also connected from the choke 10' to the negative terminal of the source B. In this instance, the tuning of the anode circuit permits accurate adjustment of the magnitude and phase of the impedance to radio frequency currents in the anode circuit.

An electron discharge tube of the pentode type readily lends itself to power grid leak detection when it embodies any of the arrangements, explained hereinbefore, for suppressing radio frequency current in the anode circuit. The pentode tube construction is well known to those skilled in the art, and need only be described by reference to Fig. 6, as including beside the usual control electrode, cathode and anode, a screen element 30 and an auxiliary electrode 31, the latter being disposed between the anode and screen element, and connected to the midpoint of the cathode.

The element 30 receives potential from the source B, through a radio frequency choke 10, as shown in connection with the detector tube in Fig. 1. A by-pass capacity 24 is shunted across the source B. As already explained, the high impedance 10 functions to produce the balancing radio frequency voltage. A pentode tube serves as a detector-amplifier in this way, and can be directly connected to a speaker, or the like.

While I have indicated and described several systems for carrying my invention into effect, it will be apparent to one skilled in the art that my invention is by no means limited to the particular organizations shown and described, but that many modifications in the circuit arrangements, as well as in the apparatus employed, may be made without departing from the scope of my invention as set forth in the appended claims.

What I claim is:

1. A method of operating an electron discharge tube, provided with a cathode, anode and grid electrode, as a power detector of the grid rectification type, which consists in impressing signal modulated radio frequency energy of relatively high intensity upon the grid electrode of the tube, maintaining a substantially linear relation between the detector output energy and the signal input energy up to said high intensity by establishing in the external anode circuit of said tube a path of high impedance to the flow of radio frequency current, and impressing the output energy of the said detector upon a means for rendering said signals discernible.

2. In combination, means for collecting, and amplifying to a high level modulated radio frequency energy, means for detecting said ampli-

fied energy comprising an electron discharge tube provided with a cathode, anode, control electrode and a screen element, the tube input circuit being arranged for grid detection, and means disposed in the screen element circuit offering a high impedance to the flow of radio frequency current in the anode circuit of the tube thereby increasing the audio frequency output thereof.

3. In combination, means for collecting, and amplifying to a high level, modulated radio frequency energy, means for detecting said amplified energy comprising an electron discharge tube including a cathode, anode, control electrode and a screen element, means connected with the control electrode and cathode for operating the tube as a grid leak detector, and means connected to the screen element circuit and anode circuit of the tube for substantially diminishing the flow of radio frequency current in the anode circuit of the tube and increasing the low frequency output thereof.

4. In combination in a combined detector and amplifier circuit, an electron discharge tube provided with a cathode, a single anode, control electrode at cathode potential, the tube input circuit being arranged for grid detection, and means in the screen element circuit for substantially reducing the flow of radio frequency current in the anode circuit and increasing the low frequency output of the detector.

5. A method of operating a grid leak detector including a screen electrode with radio frequency signal inputs of an intensity normally resulting in a decrease in the audio frequency output of the detector which consists in collecting such signals, amplifying the collected signals to said intensity, impressing the amplified signals on the control grid circuit of the detector, and simultaneously producing a radio frequency voltage in the screen electrode circuit of the detector of a magnitude and phase sufficient to substantially suppress the radio frequency component of signal current in the detector anode circuit and thereby prevent said detector audio output decrease.

6. In combination, means for collecting, and amplifying to a high level modulated radio frequency energy, means for detecting said amplified energy comprising an electron discharge tube provided with a cathode, anode, control electrode and a screen element, the tube input circuit being arranged for grid detection, and means disposed in the screen element circuit offering a high impedance to the flow of radio frequency current in the anode circuit of the tube thereby increasing the audio frequency output thereof, said last mentioned means consisting of a resonant circuit.

7. In combination, means for collecting, and amplifying to a high level modulated radio frequency energy, means for detecting said amplified energy comprising an electron discharge tube provided with a cathode, anode, control electrode and a screen element, the tube input circuit being arranged for grid detection, and means disposed in the screen element circuit offering a high impedance to the flow of radio frequency current in the anode circuit of the tube thereby increasing the audio frequency output thereof, said last mentioned means consisting of a resonant circuit including a variable condenser.

8. In combination, means for collecting, and amplifying to a high level modulated radio frequency energy, means for detecting said amplified energy comprising an electron discharge tube provided with a cathode, anode, control electrode

and a screen element, the tube input circuit being arranged for grid detection, and means including a tuned circuit disposed in the anode circuit offering a high impedance to the flow of radio frequency current in the anode circuit of the tube thereby increasing the audio frequency output thereof.

9. In combination with a detector stage of the grid rectification type, a source of signal energy varying in intensity over a wide range, an audio frequency load circuit, said stage including a tube

provided with a cathode, a signal cold electrode, and at least one positive cold electrode, a connection from the positive electrode to said load circuit, and means connected to the positive electrode circuit for substantially suppressing the radio frequency component in said load circuit whereby the detected output energy of said stage is substantially linearly related to the signal input energy over said range.

WILLIAM A. HARRIS. 10
